UNITED STATES PATENT OFFICE

110,006

DESIGN FOR A COMBINED MAKE-UP BOX AND MIRROR

Carroll K. Marcell, New York, N. Y.

Application February 3, 1938, Serial No. 74,841

Term of patent 3½ years

To all whom it may concern:

Be it known that I, Carroll K. Marcell, a citizen of the United States, residing at New York, in the county and State of New York, have invented a new, original, and ornamental Design for a Combined Make-Up Box and Mirror, of which the following is a specification, reference being had to the accompanying drawing, forming part thereof.

The figure is a perspective view of a combined make-up box and mirror, showing my new design, with the top lid in partially open position; the rear and other side, not shown, are substantially plain. The lining on the drawing indicates a contrasting color appearance.

I claim:

The ornamental design for a combined make-up box and mirror, as shown, and described.

CARROLL K. MARCELL.
